UNITED STATES PATENT OFFICE.

SIMON P. NISSLER, OF CHICAGO, ILLINOIS.

DESIGN FOR A SEAT.

59,907.

Specification for Design.

Patented Dec. 6, 1921.

Application filed July 20, 1921. Serial No. 486,276. Term of patent 7 years.

To all whom it may concern:

Be it known that I, SIMON P. NISSLER, a citizen of the United States, residing at Chicago, in the county of Cook and State of Illinois, have invented a new, original, and ornamental Design for a Seat, of which the following is a specification, reference being had to the accompanying drawings, forming part thereof.

Fig. 2 is a top plan view of the same.

I claim:

The ornamental design for a seat, as shown.

SIMON P. NISSLER.
